UNITED STATES PATENT OFFICE.

HENDRICK B. CEASE, OF HAVANA, ILLINOIS.

GRAIN-DRILL.

SPECIFICATION forming part of Letters Patent No. 391,298, dated October 16, 1888.

Application filed May 17, 1888. Serial No. 274,166. (No model.)

To all whom it may concern:

Be it known that I, HENDRICK B. CEASE, a citizen of the United States, residing at Havana, in the county of Mason and State of Illinois, have invented certain new and useful Improvements in Grain-Drills; and I do hereby declare the following to be a full, clear, and exact description of the invention, such as will enable others skilled in the art to which it appertains to make and use the same.

My invention relates to an improvement in grain-drills; and it consists in the construction and arrangement of parts, more fully herein-after described, and definitely pointed out in the claims.

The object of my invention is to provide a grain-drill which will be simple in its construction, positive in its action, and arranged in a manner to admit of its utility in rough as well as smooth ground with the same effective result.

A further object of my invention is to so arrange the different parts of a drill that the press-wheels will be allowed an independent vertical movement, and the adjustment of the runners and flukes may be accomplished with ease and precision by the operator from his seat on the drill.

I attain these objects by the mechanism illustrated in the accompanying drawings, wherein like letters of reference indicate corresponding parts in the several views, and in which—

Figure 1 is a longitudinal vertical section. Fig. 2 is a rear view. Fig. 3 is a detail view, in perspective, of a pair of runners and their spring attachment. Fig. 4 is a detail view of the operating-lever. Fig. 5 is a detail view, in section, of a joint.

In the drawings, A represents the front frame and B the rear frame, the former consisting of side bars, A', and cross-bars A² and A³, extending the entire width of the machine. The hopper or seed-box (not shown) is mounted on the forward frame, it being provided with the usual mechanism for feeding the grain. Situated beneath the front frame and supporting the same are the flukes D and their runners D', which are constructed in the usual manner. In attaching the runners D' to the frame A, I employ a series of side braces, D², extending up obliquely from the fluke D to the cross-bar A³ of frame A, at which point they

are hinged or pivoted, as at d. These braces, as shown in Fig. 3, are made integral with the fluke D on each side thereof at a point midway the length of the fluke, and diverge laterally in opposite directions to more effectively resist lateral strain on the flukes and runners. The upper ends of the runners D' are rigidly secured between the braces D² by a bolt or rod, d', passing through their ends and secured in the said braces. By this construction it will be seen that the runner and fluke are held firmly together and prevented from moving out of alignment. By hinging the runners to the cross-bar an independent vertical movement is permitted them; and to at all times retain the same in their proper working position and admit of their being forced up in case of their coming in contact with obstructions, connecting-bars E and springs F are employed, the former connecting pairs of flukes, they being secured to the rear of the same by suitable pins, e, passing through elongated slots e', formed in the ends of the bars, thus allowing an independent movement of each fluke. The springs F are made fast to the frame A and extend down and back to the connecting-bars E. Their free ends, entering an aperture in the center of said bars, serve to force the flukes down and hold them in place, but permit their vertical play.

The frame B is composed of a series of separate frames, B', having side bars, b, and end bars, b', the inner ends of the bars b being hinged or connected by ball-and-socket joints or hinges b² to the front frame, A, so that an easy vertical movement of the frames may be had and a slight lateral vibration or tilting movement admitted to prevent the wrenching of the frames in case of obstructions or unevenness of the ground.

Mounted on axles F', journaled on the frames B', are press-wheels B², which correspond in number to and are placed in alignment with the flukes, they trailing in the furrow made by the same to press the soil on the grain in a manner well known in the art. To secure an independent vertical movement of the wheels in the frames, the frames are made separate and have separate connections with the front frame, while their rear ends are united by pivoted cross-bars H H', on which the seat-supporting standards are secured.

The cross-bars H', as shown in Fig. 2, are curved or bow-shaped and extend from the center of the end bars of the outer frames to the center of the end bars of the inner frame, 5 their ends being pivoted to said bars. The bar H is preferably rectangular and extends from the crown of one of the bars H' to the crown of the other bar H', and is pivoted at said points. This construction admits the respective frames to move vertically independent of each other, and forms a support for the seat.

I represents the inclined seat-supporting frame, consisting of parallel bars united at their 15 upper ends and pivoted to an arm, K, on the front frame at their lower ends. The upper ends of this frame I are supported by the standards i, extending from the cross-bar H, heretofore referred to. The projecting arm or 20 lever K is secured rigidly to the under side of the front frame and projects back and slightly downward between the two inner frames, B', for tilting the front frame up or down to force the flukes in or out, according to the requirement 25 of the soil. To enable the operator to readily manipulate this arm, a bell-crank lever, L, is employed, which is fulcrumed and rigidly secured at its angle to a lateral pin, o, journaled in the lower ends of frames L', extending 30 from the parallel bars of frame I. The horizontal arm of lever L extends forward and has a link, m, pivoted on its end, which is in turn secured to the rear end of arm K. The vertical arm of the lever L is carried up and 35 has an inclined strap, l, secured thereto, which extends down and is made fast to the end of the horizontal arm of the lever. This strap l has an elongated vertical slot, l', formed therein about midway its length, as shown in Fig. 4, 40 through which passes an operating-handle, n, the lower end of which is pivoted on the fulcrum-pin o of the lever L, its upper end passing through the parallel bars of beam I. To enable the operator to manipulate the said arm K with 45 his feet and to give a more extended movement to the lever L, the fulcrum-pin o of the lever is extended out beyond the sides of the frames L', and has vertical arms O, secured rigidly thereon, extending up within reach of 50 the operator, so that by forcing the arms O back or forward the horizontal arm of the lever L is depressed or elevated, as the case may be. By this construction it will be seen that the lever L is worked either by the handle n or the arms O. In the former case, the 55 handle coming in contact with the end walls of the slot in strip l, the handle n is thus enabled to force the horizontal arm of the lever down or up; but owing to its movement in the slot it is prevented from moving it to its full extent, in which case the foot arms O, which are secured at the fulcrum-point of the lever, are brought into play and the required movement of the lever obtained.

65 The operation of the machine, as above described, is as follows: As the runners D' pass over and through the soil, they are held to

their work by the action of spring F, and in case one of said runners should meet with an obstruction the spring will be compressed, 70 and owing to the lateral slot in the end of bar E the vertical movement of the runner is permitted without binding or affecting the other or companion runner; or, if the runners should simultaneously meet with an obstruction the 75 spring would be compressed, permitting them to freely travel over the obstruction and immediately force them to their normal position after passing over the same.

When it is desired to force the runners into 80 or out of the ground, the lever L, which is attached to the arm K, is moved either up or down, thereby moving the forward frame to an upward or downward incline, as desired.

In uniting the rear of frames B', in the manner described, I am able to secure a more positive connection than has been the case heretofore in this style of machine.

It is evident that many minor changes in the construction and arrangement of the parts 90 of my improvement can be made and substituted for those shown and described without in the least departing from the nature and principle of my invention.

I am aware that rear frames have heretofore been connected in a manner which allows an independent movement, and this I do not broadly claim.

Having thus described my invention, what I 95 claim as new, and desire to secure by Letters 100 Patent, is—

1. In a grain-drill, the combination, with a frame and a pair of flukes, of a bar connecting the same and a spring connected with said bar for normally retaining said flukes in position, 105 substantially as described.

2. In a grain-drill, the combination, with a frame and a pair of flukes, of a bar connecting the same, and a curved spring secured to said frame and resting on said bar, whereby the 110 flukes are retained in position and allowed a vertical movement, substantially as described.

3. In a grain-drill, the combination, with a frame and flukes, of bars connecting the flukes, having elongated slots in their ends, and springs 115 secured to said frame in advance of said flukes and extended down and back to said bars and resting on the same, substantially as described.

4. In a grain-drill, the combination, with a frame, of flukes having braces secured to their 120 sides, said braces extending up obliquely and diverging laterally in opposite directions, their upper ends being hinged to said frame, substantially as described.

5. In a grain-drill, the combination, with 125 the frame, of flukes having runners attached thereto, laterally-diverging braces secured to the sides of said flukes and extending up to said frame, said runners having their upper ends secured to and between the said braces, 130 substantially as described.

6. The combination, in a grain-drill, of a frame, flukes having lateral braces hinged to said frame, runners secured to said braces and

flukes, bars connecting said flukes in pairs, and springs secured to said frame and resting on said bars, substantially as described.

7. In a grain-drill, the combination, with 5 the forward frame, of a series of rear frames having press-wheels mounted thereon and a series of ball-and-socket hinges connecting said forward frame with the rear frames, substantially as described.

10 8. In a grain-drill, the combination, with the forward frame, of a series of frames hinged thereto, presser-wheels mounted in said latter frames, bow-shaped cross-pieces pivoted at each end on the respective tops of the end 15 bars of the said series of frames behind the wheels, a cross-piece connecting said bow-shaped pieces, and seat-supporting standards secured to the connecting cross-piece, substantially as described.

20 9. In a grain-drill, the combination, with the front and rear frames, of a rearwardly-extending arm secured to said front frame, a seat-supporting beam secured on said arm, a bell-crank lever fulcrumed in said beam and

connected to said arm, said lever having upwardly-extending arms rigidly secured thereto at its angle, an elongated slotted strip connecting the ends of said lever, and a handle working in said slot, substantially as described.

10 10. In a grain-drill, the combination, with 30 the front and rear frames, of a rearwardly-extending arm secured to said front frame, a seat-supporting beam secured to said arm, a pendent frame secured to said beam, a bell-crank lever fulcrumed at its angle in said 35 frame and having its end secured to said arm, upwardly-extending arms rigidly secured to said lever, a strap having a vertical slot therein connecting the ends of said lever, and a handle working in said slot and pivoted on the 40 fulcrum of said lever, substantially as described.

In testimony whereof I affix my signature in presence of two witnesses.

HENDRICK B. CEASE.
